(57) **CLAIM**

The ornamental design for a rear light for motor vehicle as shown and described.

DESCRIPTION

FIG. 1 is a perspective view of a rear light for motor vehicle according to a first embodiment showing my new design;

FIG. 2 is a front view thereof;

FIG. 3 is a left view thereof; and

FIG. 4 is a top view thereof.

FIG. 5 is a perspective view of a rear light for motor vehicle according to a second embodiment showing my new design;

FIG. 6 is a front view thereof;

FIG. 7 is a right view thereof; and,

FIG. 8 is a top view thereof.

The broken lines in the drawings illustrate the boundary between claimed and unclaimed subject matter.
